UNITED STATES PATENT OFFICE.

HENRY A. HUEFFNER AND LEVI LASH, OF VIRGINIA, ILLINOIS.

DUST-ARRESTER.

SPECIFICATION forming part of Letters Patent No. 519,958, dated May 15, 1894.

Application filed June 8, 1893. Serial No. 476,994. (No model.)

To all whom it may concern:

Be it known that we, HENRY A. HUEFFNER and LEVI LASH, both citizens of the United States, and residents of Virginia, in the county 5 of Cass and State of Illinois, have invented new and useful Improvements in Dust-Arresters, of which the following is a specification.

In order that our invention may be fully understood, we will proceed to describe it with reference to the accompanying drawings, in which—

Figure I is a side elevation of our improved dust-arrester. Fig. II is a vertical longitudinal section thereof on the line II—II of Fig. III. Fig. III is a vertical transverse section of the same on the line III—III of Fig. II. Fig. IV is an enlarged horizontal section on the line IV—IV of Fig. V. Fig. V is an enlarged vertical section on the line V—V of Fig. IV.

1 is the casing.

9 is a rotary fan journaled in brackets 12 secured to the sides of the casing.

25 16 is the fan-drum having air-inlets 21 in its sides.

17 is a floor extending from the fan-drum and forming in connection with the top of the casing an air-channel 18, leading from the air-drum. An angular projection 22 on the front end of the casing forms in connection with a vertical wall 27 a continuation of the air-channel 18 and is connected with the top and floor respectively by means of curved plates 35 24, 28.

26 is a separating chamber, with which the air-channel connects, located beneath the ceiling 25.

29 is an inclined wall extending from the 40 ceiling to the drum.

30 is a series of supply chutes arranged in steps discharging into their respective hoppers 38 located over the primary separating chambers 34. Located between the hoppers 45 are deflectors 169. The supply from the hoppers is regulated by the feed rolls 42 mounted in journal boxes 182, in connection with the pendent valves 46, adjusted by arms 54, supported on spiral springs 58, which encircle 50 supporting rods 62, depending from the brackets 74 on which they are supported by thumb nuts 78. An angular projection 82 is secured

to the forward side of each separating chamber to retard the elevation of the heavier grade of material which is deposited in the 55 tight bottom of the same. Air ports 86 in the rear sides of the chambers opposite the projections provide air passages for the current created by the fan. These air-ports are controlled by valves 90, having arms 94 held by set screws 98 working in curved slotted holders 102.

170 is a port in the ceiling 25 providing a direct passage for a portion of the air current from the chamber 172 beneath, to the suction-chamber 173 above. This port is controlled by a valve 174 having an arm 175 secured by a set screw 176 working in a curved slotted holder 177. 106 are discharge ports from the chambers controlled by valves 110. 70

114 is the final primary separating chamber provided with a discharge port 115 controlled by a valve 116. The partition 178 is located between the last chamber 34 and the chamber 114 and is provided with a flat end 75 179, against which the hinged deflector 120 works.

180 are side chambers connected with the fan-drum. 117 are hinged current deflectors having arms 125 secured by set screws 129 80 working in curved slotted holders 133. The deflector 120 has similar means for its adjustment. 137 is a dust chamber, located beneath the chamber 26, having a concave bed 138 in the floor 139. 85

140 is a screw conveyer working in the bed and discharging the material through a port 141 controlled by a valve 142.

145 is an inclined overhanging screen extending from the ceiling to the floor 139. 90

146 is a collecting and deflecting apparatus located over a flour chamber 152. Within the chamber 26 behind the screen 145 an endless chain 147 is mounted on rollers 148, carried by shafts 149 journaled in boxes 150 which 95 are secured to the sides of the casing. A brush 151 is secured to the chain and clears the meshes of the screen.

153 is a concave bed to the flour bin in which a screw conveyer 168 works for discharging the material through a port 154 controlled by a valve 155. The shaft 156 of this conveyer is journaled in boxes 157 secured to the sides of the casing. 100

The apparatus 146 has a perforated base 158 located over the flour bin and discharges the material through the outlets 159 into the bin. The apparatus has a series of parallel partitions 160, that extend from side to side of the casing, except for a series of ports 161 through which the air current passes. Cross partitions 162 extend at certain intervals, throughout the whole length of parallel partitions 160. The parallel partitions are set at an incline from the perpendicular, and are incised above with a top plate 163.

A series of deflecting frames 164 in I form, with inclined plates 165, which project from and connect the end plates 166, constitute a system of deflectors and the inclined plates lead the air currents to the ports 161. The course of the laden air currents, after they pass through the screen 145, (which has prevented the passage of most of the impurities) is through certain of the inlets 161, into the chambers 167, as shown by the arrows in Figs. IV and V and then passing through the chambers between certain of the cross partitions, the currents are deflected along the next partitions, until they reach their next ports 161 and so on throughout their course, the heavier ingredient as it eddies around is precipitated against the deflectors and always tends to a lower level than the lighter products, and the heavy product is thus mainly precipitated through the outlets 159 into the flour bin 152, from which it is carried by the screw conveyor 168 and discharged through the port 154. The current that is both forced and drawn on its course by the rotary fan thus effects as above described the separation of the particles that are required to be disassociated and then, almost pure, passes out through the final outlets 161, into the chamber 172, thence through the inlets 86 into the said primary separating chambers, where said pure air becomes again laden with the constituents of the middlings under the rapid suction and forced current, generated by the fan, it is driven on its renewed circuit.

Having thus described our invention, the following is what we claim as new therein and desire to secure by Letters Patent:

1. The combination of the casing, the fan-drum, having air-inlets, the floor 17 the vertical wall 27, the ceiling 25, and the inclined wall 29, forming in connection with the casing the air channel 18, the chambers 26, 172, and 173 and side chambers 180, connected with the fan-drum, the inclined series of primary separating chambers 34, and an adjustable valve for controlling the current, in advance of the primary separating chambers, between the inclined wall and the first primary separating chamber; substantially as described.

2. The combination with the casing of the collecting and deflecting apparatus 146, comprising a base formed with discharge ports, a top plate, parallel longitudinal partitions formed with ports, imperforate cross parti-

tions, and the I-shaped frames, the air channel, and the rotary fan; substantially as described.

3. The combination of the casing, the air-channel, the vertically inclined endless chain carrying a brush, the vertically inclined screen against which the brush operates, the vertically inclined collecting and deflecting apparatus comprising a base formed with discharge ports, a top plate parallel longitudinal partitions formed with ports, the imperforate transverse partitions and the I-shaped frames, and a rotary fan; substantially as described. 70

4. The combination, with the casing; of the air-channel, the vertically inclined endless chain, carrying a brush, the vertically inclined screen upon which the brush operates, the primary separating chamber, the vertically inclined collecting and deflecting apparatus located between the screen and chamber and a rotary fan; substantially as described. 80

5. The combination, with the casing; of the fan-drum, the floor, the vertical wall the ceiling having a port, the inclined wall, the valve controlling the port, the air-channel, the vertically inclined endless chain, carrying a brush, the vertically inclined screen, the primary separating chamber, the vertically inclined collecting and deflecting apparatus located between the screen and chamber, and a rotary fan; substantially as described. 90

6. The combination, with the casing; of the fan-drum, the floor, the vertical wall, the ceiling having a port, the inclined wall, the valve controlling the port, the air channel, the main bin, the vertically inclined endless brush-chain, located over the main bin, the vertically inclined screen against which the brush operates, the flour bin, the vertically inclined collecting and deflecting apparatus located over the flour bin, the primary separating chambers located in front of the apparatus, and a rotary fan; substantially as described. 100

7. The combination, with the casing; of the floor, the vertical wall, the ceiling, the inclined wall, the main bin, the screen and the endless brush chain located over the main bin, the flour bin, the collecting and deflecting apparatus located over the flour bin, a primary separating chamber located in front of the apparatus, the side-chambers, the fan-drum located between the side chambers, and the rotary fan; substantially as described. 110

8. The combination of the rotary fan, the outer and inner casings, the main bin, the screen, the endless chain carrying a brush, the flour bin, and the collecting and deflecting apparatus comprising a base having discharge ports, the parallel longitudinal partitions formed with ports, the cross partitions, and the I shaped frames; substantially as described. 120

9. The combination, with the casing; of the primary separating chamber 34, having a port 86 in its rear side, a valve 90 controlling the port, an angular projection 82 located on the front side of the chamber opposite the port, 130

the deflector 169 in front of the chamber, a feed roll 42, the hopper 38 located over the feed roll having a supply chute 30, a valve 46 controlling the outlet to the hopper, the hinged current deflector 117 controlling the passage between the front walls of the hopper and chamber, the inner casing, the air-channel, and a rotary fan; substantially as described.

5 10. A collecting and deflecting apparatus comprising a perforated base, the parallel longitudinal partitions formed with ports, the cross partitions and the I shaped frames; substantially as described.

11. The combination of the rotary fan, the outer and inner casings, the main bin, the screen, the endless chain carrying a brush, the flour bin, the collecting and deflecting apparatus, the primary separating chambers arranged in steps in front of the apparatus, the

final chamber 114, and the upwardly extending hinged deflector 120; substantially as described.

12. A dust arrester comprising the outer and inner casings, the air-channel 18, the chambers 26, 172, 173, the dust bin 137, the screw conveyer 140 located in the dust bin, the endless brush chain 147, the screen 145, the flour bin 152, the screw conveyer 168, located in the flour bin, the collecting and deflecting apparatus 146, the primary separating chamber 34, the hopper 38, the deflector 117 and the rotary fan; substantially as described.
